UNITED STATES PATENT OFFICE.

ISAAC H. WEINBERG AND CHARLES F. BISBING, OF NEW YORK, N. Y.

DESIGN FOR A PARASOL OR UMBRELLA.

56,043.

Specification for Design.

Patented Aug. 10, 1920.

Application filed April 3, 1920. Serial No. 371,165. Term of patent 7 years.

To all whom it may concern:

Be it known that we, ISAAC H. WEINBERG and CHARLES F. BISBING, both citizens of the United States, and residents of the city of New York, borough of Manhattan, in the county of New York and State of New York, have invented a new, original, and ornamental Design for a Parasol or Umbrella, of which the following is a specification, reference being had to the accompanying drawing, forming part thereof.

Fig. 2 is a view in front elevation.

Fig. 3 is an end view showing our new design.

We claim:

The ornamental design for a parasol or umbrella, as shown.

ISAAC H. WEINBERG.
CHARLES F. BISBING.
